Specification for Design.

Patented June 1, 1920.

Application filed October 4, 1918. Serial No. 256,909. Term of patent 14 years.

To all whom it may concern:

Be it known that I, LOUIS S. KURTZMANN, a citizen of the United States, residing at Buffalo, in the county of Erie and State of New York, have invented a new, original, and ornamental Design for Phonograph-Cases, of which the following is a specification, reference being had to the accompanying drawing, forming a part thereof.

In the accompanying drawings:

Figure 1 is a perspective view of a phonograph case embodying the invention.

Fig. 2 is a front elevation thereof.

Fig. 3 is a top plan view thereof.

The phonograph case shown comprises a transparent top plate A and transparent side and rear walls B inclosing a horn C. A turn-table or rotary disk D made of transparent material, is also provided.

I claim:

The ornamental design for a phonograph case as shown and described.

LOUIS S. KURTZMANN.
